AIR PUMP FOR CAMPING STOVES

William Albert Folke, Upplands Vasby, Sweden, assignor
to Aktiebolaget Optimus, Upplands Vasby, Sweden

Filed Aug. 5, 1975, Ser. No. 602,183

Claims priority, application Sweden Feb. 5, 1975

Term of patent 14 years

Int. Cl. D23—01

U.S. Cl. D23—15

FIG. 1

FIG. 2

FIG. 3

FIG. 1 is a perspective view of an air pump for camping stoves, showing my new design;

FIG. 2 is another perspective view taken from the side and end opposite those shown in FIG. 1; and

FIG. 3 is an elevational view taken from the end shown in FIG. 2.

I claim:

The ornamental design for an air pump for camping stoves, as shown.
